UNITED STATES PATENT OFFICE.

DUDLEY BAIRD, OF BERKELEY, CALIFORNIA, ASSIGNOR TO GENERAL CHEMICAL COMPANY, OF NEW YORK, N. Y., A CORPORATION OF NEW YORK.

RABBLING ARM FOR ROASTING FURNACES.

Application filed February 5, 1920. Serial No. 356,553.

To all whom it may concern:

Be it known that I, DUDLEY BAIRD, a citizen of the United States, and a resident of Berkeley, in the county of Alameda, State of California, have invented certain new and useful Improvements in Rabbling Arms for Roasting Furnaces, of which the following is a specification.

My invention relates to ore roasting furnaces of that type in which the interior of the rabble arm is divided into a plurality of passages connecting respectively with a plurality of passages in the central shaft (see, for instance, United States Letters Patent to Herreshoff, No. 976,175, November 22, 1910), and has for its object to improve the construction of the rabble arms thereof.

The particular object of my invention is a rabble arm embodying an external tubular member which supports the rabble teeth, and an internal tubular member through which latter a cooling fluid such as air may be introduced to the interior of the external member to reduce the temperature thereof. The novel features of my invention are pointed out in the appended claims.

My invention may be embodied for instance in a construction such as shown, for purpose of illustration, in the drawing, in which Fig. 1 is a horizontal section of a rabble arm and of the central rotatable shaft of the furnace to which it is attached; Fig. 2 is a vertical section of a portion of my rabble arm and of so much of the central rotatable shaft as is necessary to illustrate the connection between rabble arm and shaft; Fig. 3 is an end view of the inner end of the rabble arm; Fig. 4 is a top view, and Fig. 5 a bottom view, of the inner end of my rabble arm.

The central rotatable shaft is formed in any suitable manner so as to have a central passage enclosed by an inner wall 1 and an annular passage enclosed between said inner wall 1 and an outer wall 2; ribs 3, 3 are preferably provided in order to increase the rigidity of the central shaft in the region of the connection with the rabble arm. Suitable openings are provided in the inner and outer walls to receive the end of the rabble arm, the opening in the outer wall being preferably surrounded and defined by an annular flange such as 2'. The rabble

arm consists of an outer member 4 of any suitable tubular shape, and may include any features commonly found in arms of this type for instance the opening at the outer end thereof to permit access to the interior from such end. It may be made of any suitable material, but is preferably made of cast iron, and is arranged to support rabble teeth of any desired construction, for instance those shown in United States Letters Patent, No. 1,234,408, July 24, 1917. This outer arm is provided with supporting means such as ribs 5—5 arranged in the interior portion of the inner extremity of the rabble arm. These supporting means preferably extend into the annular chamber formed between walls 1 and 2 and preferably terminate in a joint forming member such as the ferrule 7 adapted to make close contact with the walls of the aperture in the inner wall 1. The interior member 6 of the rabble arm is of tubular shape, and may be made of any suitable material, preferably steel, and is attached by frictional engagement or otherwise to the supporting means 5 and preferably also to the joint forming member 7.

The flange 2' is preferably provided with an opening in its upper portion, and the external member with a corresponding opening near its inner end, such openings being adapted to be placed in alignment. When these openings are in alignment a lock pin 8 may be inserted thereinto so as to lock the arm and rotary shaft in proper relationship. The lock pin 8 may be of any suitable construction and is preferably provided with a head of a larger diameter than the shank and with a stop shoulder at a distance from the head to limit the movement of the pin into the openings and to provide a space into which the end of a suitable tool is inserted for the purpose of withdrawing the pin so as to permit the removal of the arm from the rotary shaft, in the manner fully described in United States Letters Patent No. 1,191,848, July 18, 1916.

In order to permit a ready alignment of these two openings preparatory to the insertion of the lock pin 8, the flange 2', and the external member 4, may be provided with suitable positioning means such as the 105 wedge-shaped extension piece 2" on the

former, and two suitably spaced stop members 4'-4' on the latter adapted to engage with said extension piece when the relation of the flange and rabble arm is such that the 5 two openings are in alignment.

When it is desired to remove the arm for purpose of repair or exchange, the lock pin 8 is removed and the arm is pulled away, preferably through the open furnace door. 10 When the exterior member is removed, the interior member, being attached thereto, is removed with it, and when the arm is inserted in place but one operation is necessary as both interior member and exterior member 15 are combined in the form of a unit, and are so arranged that no part of the interior member comes in contact with any part of the central shaft. It is necessary, therefore, to adjust the relation of only two elements, to 20 wit, the external member of the rabble arm and the central shaft, instead of, as heretofore, adjusting the exterior member and the interior member separately to different portions of the central shaft structure. This 25 forms one of the advantages of my invention.

Another advantage of my invention, as embodied in the structure shown in the drawings, is that the interior member is supported 30 at points located outside of the periphery of the central shaft while yet having its outer end free, instead of being supported only by the inner wall of the central shaft as in various constructions known to the 35 prior art, or of being supported at one or more points nearer the outer end of the rabble arm. It is obvious that in that portion of the rabble arm directly exposed to the hot furnace gases the circulation should 40 be as free as possible, and that therefore any contact between the interior member and the exterior member in such portion should be avoided, and this I have accomplished by placing my support within that portion of 45 the rabble arm which is protected by the central shaft and the flange 2'. In addition to their other functions, the ribs 5, which, in the illustrated example, constitute the support referred to, define radial fluid 50 passages between the interior and exterior members near the inner ends thereof.

In my construction the interior member may be supported in its entirety by the exterior member, while still extending centrally thereof, so as to permit a free circulation 55 of the cooling medium along the entire inner surface of the exterior member except such small portion thereof as is occupied by

the supporting means for the interior member.

It is obvious that I may embody my invention in constructions other than those shown in the drawings, and that for instance the form, arrangement and attachment of the supporting members may be varied, and that the arrangement for uniting the rabble arm to the central shaft may be varied, in many ways, without departing from the spirit of my invention. It is, of course, obvious, that the invention is applicable only to the type of rabble arm which permits connection of the external member and of the internal member, with two passages, respectively, in a central shaft, to permit circulation of a cooling fluid, such as air, through 75 said members, and it is to a rabble arm of this type to which I refer in my claims.

I claim:

1. A rabble arm construction of the type described comprising an external tubular member, an internal tubular member, means provided at the inner end of said external member for supporting said internal member within the external member and spaced from the walls thereof, said means being located 80 partly without said external member and defining radial fluid passages between said members, and a joint-forming member carried by said supporting means exteriorly of 85 said external member.

2. A rabble arm construction of the type described comprising an external tubular member, an internal tubular member projecting beyond the inner end of said external member, radially-extending devices spaced 90 from each other on one of said members near the inner end thereof for supporting said internal member within the external member and spaced from the walls thereof, said devices projecting beyond the inner end of 100 said external member, and a joint-forming member carried by the outer ends of said devices.

3. A rabble arm construction of the type described comprising a tubular member, radially extending devices spaced from each other attached to such member and projecting beyond the same, a joint forming member carried by the outer ends of said devices, and an internal tubular member 110 supported by said devices and extending to said joint forming member.

In testimony whereof I have hereto set my hand.

DUDLEY BAIRD.
